UNITED STATES PATENT OFFICE.

FRANK J. FREY, OF QUINCY, AND HENRY A. LENGFELDER, OF BELLEVILLE, ILLINOIS, ASSIGNEES TO QUEEN CITY STOVE & RANGE COMPANY, OF BELLEVILLE, ILLINOIS.

DESIGN FOR A STOVE.

SPECIFICATION forming part of Design No. 37,285, dated January 3, 1905.

Application filed December 8, 1904. Serial No. 236,071. Term of patent 7 years.

To all whom it may concern:

Be it known that we, FRANK J. FREY, residing at Quincy, county of Adams, and HENRY A. LENGFELDER, residing at Belleville, county of St. Clair, State of Illinois, citizens of the United States, have invented a certain new, original, and ornamental Design for Stoves, of which the following is a specification, reference being had therein to the accompanying drawing, showing a perspective of the new design for stoves.

What we claim as new, and desire to secure by Letters Patent, is—

The ornamental design for a stove, as shown.

FRANK J. FREY.
HENRY A. LENGFELDER.
